[57] CLAIM

The ornamental design for a hooded towel, as shown and described.

DESCRIPTION

FIG. 1 is a front perspective view of a hooded towel showing the design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is a front elevational view of a hooded towel showing a second embodiment of the design, the sole difference being the shape of the towel.
